UNITED STATES PATENT OFFICE.

GODFREY H. SWANTON, OF MELBOURNE, AND ARTHUR F. ECHBERG, OF HAWTHORN,
MELBOURNE, AUSTRALIA.

CURB.

Application filed December 8, 1923. Serial No. 679,377.

To all whom it may concern:

Be it known that we, GODFREY HERBERT SWANTON, merchant, a subject of the King of Great Britain and Ireland, and a resident of the city of Melbourne in the county of Bourke, State of Victoria, Commonwealth of Australia (whose post-office address is 346 Flinders Street, in the said city of Melbourne), and ARTHUR FREDERICK ECHBERG, consulting engineer, a subject of the King of Great Britain and Ireland, and a resident of the city of Hawthorn, a suburb of the city of Melbourne, in the county of Bourke, State of Victoria, Commonwealth of Australia (whose post-office address is 1 Rosney Street, in the said city of Hawthorn), have invented certain new and useful Improvements in Curbs, of which the following is a specification.

This invention relates to the conduits or underground passages in which gas and water mains, electric conductors and the like are laid along roadways or like places.

It is at present the usual practice to lay such pipes or conductors in a channel which is excavated from the roadway, footpath or the like, the channel being subsequently filled in with earth and also sometimes covered with a surfacing material such as asphalt.

A serious disadvantage with the above practice is the time, labor and inconvenience entailed in obtaining access to the interior of the channel for inspection and repair of the pipe lines or conductors therein. This operation necessitates the digging up of the earth or covering material and thus in many cases closing a portion of the thoroughfare to traffic.

The object of the present invention is to provide an improved construction of such conduits, which in accordance with the invention are formed of a series of special pre-cast concrete or like block units or sections. These units are adapted for laying beside the roadway and in addition to forming a readily accessible conduit are also especially shaped to form an adjacent curbing and gutter extending parallel to the conduit.

Referring to the drawings which form a part of this specification:—

Figure 1 is a fragmentary plan view of the conduit one of the covering slabs of the conduit being removed.

Figure 2 is a cross section of the conduit.

Each pre-cast block, unit or section in accordance with the invention may be of any suitable length, width and height depending upon requirements and, to form the conduit, a series of the units are placed end to end and preferably cemented together.

Formed in the upper face of each unit and extending from end to end thereof is an open topped channel 2 of suitable width and depth to accommodate the requisite pipe lines, electric conductors and the like indicated at 3. The channel 2 is bounded by an inner upstanding side wall 4 and an outer side wall 6 said walls extending parallel to each other from end to end of the unit and being connected by an intermediate or bottom portion. Extending along the inner edges or corners of the walls 4 and 6 at the top of said channel are opposite longitudinal insteps or recesses 7 forming oppositely aligned ledges or shoulders 8 to support a covering slab 9.

A series of the covering slabs 9 which may be of concrete or other suitable material, are placed end to end over the open topped channel to thus form a closed conduit, the opposite sides of the slabs being accommodated by the recesses 7 so that a substantially flush surface is formed by the top of the slabs 9 and the upper surfaces of the walls 4 and 6. The covering slabs may be cemented or otherwise suitably secured in place in such a manner that they may be easily removed to thereby permit of immediate access to the interior of the conduit formed by the channel 2.

The inner side wall 4 is adapted to adjoin or abut against the flags 11 or material of the footpath and may if desired be provided along its adjacent upper edge or corner with a longitudinal recess or instep 13 forming a shoulder or ledge 14 to support the adjoining flags 11 of the footpath.

The outer upstanding wall 6 is adapted to form a curbing member having a right angled corner 16 and vertical face 17 extending parallel to the conduit or channel 2 from end to end of the unit. A continuous curbing is thus formed when a series of the units are laid in longitudinal alignment.

Extending outwardly, from the curbing member is a flange 19 the upper surface 21 of which preferably slopes downwardly and inwardly towards the face 17 of the curbing to thereby form a drainage gutter along the

side of the roadway which is indicated at 22. The outer edge 23 of this flange is adapted to adjoin or abut against the material of the roadway 22 so that the surface of 5 the latter may lie flush with and continue the sloping cross sectional contour of the upper face 21 of said flange which constitutes the bottom of the gutter.

The upper surface of the intermediate or 10 bottom portion 5 may slope transversely downwards as at 20 towards the outer side wall 6 and external gutter and suitable drain passages 23^a may extend through said wall or curbing member to carry any moisture

15 from the interior of the conduit 2 to said gutter. In such cases the bottom of the gutter or upper face 21 of the flange 19 may be disposed at a considerably lower level than the bottom surface 20 of the conduit 2 so 20 that water cannot flow inwardly from the external gutter to the conduit. Alternatively the moisture may drain downwardly through passages 24 formed through the intermediate or bottom portion 5 of the unit.

25 The channel or conduit 2 may be formed by a pair of laterally separable parallel sections, the outer of which carries the outer upstanding wall or curbing member and the gutter flange 19 whilst the co-operating inner section carries the inner wall 4 of the conduit. The intermediate or bottom portion 5 of the structure is thus longitudinally divided as at 26 so that should it be desired 30 to extend the width of the conduit 2 or of the structure as a whole a distance piece 27 may be interposed between the longitudinally meeting edges 26 of the bottom portion 5, the cover slabs 9 being of increased width accordingly. If desired the distance piece 27 35 may be adapted to project within the channel 2 and thus divide same into a plurality of separate longitudinal compartments to accommodate different pipe lines, electric conductors or the like.

40 By means of the invention it is merely necessary to lay a series of the pre-cast units above described in longitudinal alignment between the roadway and footpath and with their ends abutting as at 30 and suitably 45 cemented together. The desired pipe lines, electric conductors or the like may be then laid within the open topped channel, which is afterwards closed by placing the covering slabs in position. To gain access to the 50 interior of the conduit it is thus merely necessary to remove one or more of the covering slabs where desired, the slab or slabs being

easily replaced and secured in position when the desired operations have been performed.

It will be evident that the invention thus 60 ensures a considerable saving of time, labor and expense in the laying of the pipe lines or conductors and also in the inspection and repair thereof, besides forming at the same time a curbing and gutter structure thereby 65 effecting a very considerable saving in the time, labor and expense hitherto involved in laying the usual separate curbing blocks and gutter slabs or stones.

Having now described our invention what 70 we claim as new and desire to secure by Letters Patent is:—

1. A concrete roadway conduit comprising a combined gutter and curbing unit which comprises a curbing member, a flange 75 on the curbing member adapted to extend into the roadway, and a bottom portion extending from the other side of said curbing member; a bottom and side wall unit having a side wall, and a bottom portion, said side 80 wall and curbing member having insteps in the upper edges thereof; a distance unit inserted adjacent and between the bottom portions of said units, said bottom portions and said distance unit forming the bottom of the 85 conduit which is above the level of the flange in order to prevent accumulation of water in the conduit; and a removable covering slab for the units adapted to seat in said insteps and being flush with the upper surface 90 of the curbing and the sidewalk.

2. A concrete roadway conduit comprising a combined gutter and curbing unit which comprises a curbing member having drain passages therein, a flange on the curbing member adapted to extend into the roadway, and a bottom portion extending from the other side of said curbing member; a bottom and side wall unit having a side wall, and a bottom portion, said side wall and 100 curbing member having insteps in the upper edges thereof; a distance unit inserted adjacent and between the bottom portions of said units, said bottom portions and said distance unit forming the bottom of the 105 conduit; and a removable covering slab for the units adapted to seat in said insteps and being flush with the upper surface of the curbing and the sidewalk.

In testimony whereof we affix our signatures.

G. H. SWANTON,
ARTHUR F. ECHBERG.
